FEED DEVICE FOR AUTOGRAPHIC
REGISTERSPercy Alfred Flawn, Lambeth, London, England,
assignor to W. H. Smith & Son Limited, London, England, a British companyApplication August 29, 1946, Serial No. 693,643
In Great Britain December 28, 1945

6 Claims. (Cl. 271—2.4)

1
This invention relates to so called autographic registers of the type (hereinafter referred to as the type described) in which a supply of continuous stationery strips is drawn from a zig-zag pack or a roll and is traversed step by step across a writing platen by feeding means operable by successive movements of an external handle or the equivalent.

In autographic registers of the type described it is desirable that a positive stop should be provided for automatically limiting the length of stationery strips fed at each step; for example, the strips may have a succession of forms printed along their length and it is important in that event that exactly one form length should be fed at each movement of the handle. It is an object of the invention to provide in an autographic register of the type described an improved form of stop mechanism for this purpose. In some autographic registers of the above type, the operating handle is rotatable and a complete revolution of the handle is required for each feeding step. A more convenient arrangement is one in which the handle is moved through only a part, say one quarter, of a revolution for each feeding step and is then returned to the starting position. The invention is particularly suitable for use with autographic registers arranged in this way.

The invention consists in an autographic register of the type described and having the characteristic feature that the driving connection between the operating handle or the equivalent and the stationery feeding means includes a feed limiting device comprising a driving member movable by the handle, a driven member operatively connected to the stationery feeding means, a stop member arranged to engage and stop the movement of the driven member (or a part in fixed driving connection therewith) after a predetermined amount of stationery has been fed and a pawl or the equivalent arranged to provide a one-way driving connection between the driving and driven members and also as a preliminary to each feeding operation to disengage the stop member.

In a preferred form of the invention the feed limiting device comprises a spindle or the equivalent constituting the driving member and arranged for oscillatory movement by the operating handle, a rotatable ring coaxial with and surrounding the spindle in spaced relationship, the ring constituting the driven member and having two or more apertures in its circumference, a stop pawl outside the ring and arranged auto-

5
matically to engage each aperture in turn from the outside to stop rotation of the ring and a driving pawl carried by the spindle in the space between the spindle and ring and arranged at the beginning of each operation of the handle in the feeding direction to engage from the inside the aperture already engaged by the stop pawl to push the stop pawl out of its engagement with the aperture and then by its engagement with the aperture to rotate the ring until the stop pawl by engagement with the next aperture prevents further movement of the ring.

10
The invention includes the inversion of the feed limiting device just described in which the stop pawl engages the apertures in the driven member from the inside thereof while the driving pawl engages the apertures from the outside of the driven member.

15
The feed limiting device may include a non-return device to prevent backward movement of the stationery. This non-return device may comprise a ratchet engaging teeth on the driven member of the feed limiting device or, preferably, the ratchet is arranged to engage a toothed wheel driven by gearing from the driven member and carried, for example, on the shaft carrying the stationery feeding means.

20
One example of an autographic register embodying a feed limiting device forming the subject of this invention will now be described with reference to the accompanying drawings in which:

25
Figure 1 is an elevation, partly in section, of the autographic register;

30
Figure 2 is a section partly broken away and on the line 2—2 in Figure 1;

35
Figure 3 is a detail view in the direction 3—3 in Figure 2 showing the feed limiting device from one side ready for operation;

40
Figure 4 is a detail view showing the feed limiting device from the other side;

45
Figures 5 and 6 are diagrammatic views of a modification of the feed limiting device; and

50
Figure 7 is a diagrammatic view of a further modification of the device.

55
In this example the autographic register comprises an outer casing 1 having a hinged cover 2 provided with a rectangular aperture 3. Within the casing and secured to the bottom of the casing by screws 4 is an inner frame 5 which carries the feeding means and a writing platen 6 positioned below the aperture 3. In use a zig-zag pack of continuous manifolding stationery is placed in a compartment 7 and is traversed step by step—each step corresponding to a printed

form—over the writing platen by the feeding means. After the stationery has passed over the platen one copy or more than one if desired is issued from the machine as indicated at 8 and another copy is fed into a record compartment 9 and refolded into zig-zag form.

The feeding means for the stationery comprise a pair of pin wheels 10 arranged to engage marginal perforations in the stationery and driven through the feed limiting device and appropriate gearing later described from the operating handle 11. The handle is arranged for manual operation through a quarter of a revolution for each feeding step and then to be returned to the starting position as shown in the drawings by the spring 12. The handle is carried on a shaft 13 supported in bearings in the inner frame 5 and an auxiliary frame 6. The shaft 13 constitutes the driving member of the feed limiting device and is provided with a grooved disc 14—or equivalent radial arm—near the end remote from the handle 11. The disc 14 has a pin 15 extending from one side face and co-operating with a slot 16 in the auxiliary frame 6 to limit the travel of the handle.

The driven member of the feed limiting device is in the form of a gear wheel 18 rotatable on the shaft. One side face of the gear wheel has an upstanding ring 19 surrounding the disc and spaced therefrom. The ring has four gaps or apertures 20 equally spaced around its circumference. The stop pawl 21 is pivoted at 22 to the auxiliary frame 6 outside the ring 19, the pivot being ahead of the operative part 23 of the pawl considered in the direction of rotation indicated by the arrow in Figure 3. The pawl is urged towards engagement with the outside of the ring by the spring 25 and the operative part of the pawl is of rectangular form which is a working fit in the apertures in the ring. The driving pawl 27 is pivoted at 28 within the groove in the disc 14 with the operative part 30 of the pawl leading the pivot considered in the direction of rotation. The pawl is of substantial length relative to the radial distance between the pivot 28 and the inside of the ring 19 so that when the pawl is in engagement with an aperture 20 in the ring and rotary movement is applied to the driving member, the pawl exerts pressure on the driven member in a direction such that there is a substantial component of pressure directed radially outwards. This component of pressure is employed to enable the driving pawl to push the stop pawl out of its engagement with the aperture.

The apertures in the ring are each of rectangular formation and in order to assist in engagement of the stop pawls with the apertures, the end faces of the two pawls are slightly curved as indicated in Figure 3.

The gear 18 constituting the driven member is in driving engagement with a smaller gear 32 integral with a gear 33 in driving engagement with a gear 34 mounted on a shaft 35 carrying the pin wheels 10. The shaft 35 also carries a ratchet wheel 36 co-operating with a pawl 38 to constitute a non-return device preventing backward movement of the stationery. In an alternative arrangement the gear 18 is in direct driving engagement with a gear on the pin wheel shaft. The gear ratio may be varied to suit forms of different lengths. For example in one construction the ratio is such that the pin wheels make one complete revolution for each quarter turn of the driving and driven members of the feed limiting device.

The operation of the feed limiting device de-

scribed above is as follows. When operating pressure is applied to the handle 11 the driving pawl 27 is pressed into engagement with the aperture in the driven member already occupied by the part 23 of the stop pawl. The driving pawl pushes the stop pawl out of engagement with the aperture and conveys rotary movement to the driven member 18. This movement continues until the stop pawl engages in the next aperture and prevents further movement of the driven member. The handle is then released and the spring returns the handle and driving pawl to their original positions ready for the next operation of the device. The quarter turn given to the driven member in this way is transmitted through the gears to the shaft carrying the pin wheels which feed a corresponding length of stationery across the writing platen.

Figures 5 and 6 show, diagrammatically, an inverse modification of the arrangement just described. In this modification the driving member consists of the shaft 50 which is arranged for oscillation by the operating handle in the manner already described and which carries a disc 51 fixed to the shaft. The driven member consists of a gear 52 rotatable on the shaft and arranged, as before, to drive a shaft carrying feeding pin wheels. The gear 52 has on one face a ring 53 formed with apertures 54. The stop pawl 55 is located within the ring 53 and is pivoted at 56 to a fixed part of the frame not shown in the diagram. The driving pawl 57 is outside the ring 53 and is pivoted at 58 to the disc 51.

The operation of this modified form of the feed limiting device is that on the application of pressure to the operating handle to rotate the shaft 50 the pawl 57 first exerts radially inward pressure on the stop pawl 55 and forces it out of engagement with the aperture 54. When the pawl 55 has been disengaged from the aperture continued pressure on the handle causes the pawl 57 by its engagement with the aperture to rotate the driven member until such time as the stop pawl drops into the next aperture 54 and prevents further rotation.

In a further modified arrangement as shown diagrammatically in Figure 7 the driving pawl 60 is pivoted at 61 on the end of an arm 62 freely mounted on the driving shaft 63. The operative part 64 of the pawl leads the pivot as considered in the driving direction. One side face of the pawl has two upstanding projections 65, 66, one on either side of the pivot 61. The driving shaft 63 has a rigidly attached arm 67 of which the free end lies between the aforesaid projections 65, 66. In this arrangement when feeding pressure is applied to the handle the fixed arm engages the projection 65 on the pawl on the leading side of the pivot and rocks the pawl about the pivot thereby causing the operative part 64 of the pawl to move outwardly and to disengage the stop pawl 68 from the driven member 69. When the feeding operation is completed and the handle starts to return the fixed arm engages the other projection 66 on the driving pawl and rocks the pawl about its pivot to disengage it from the driving member.

I claim:

1. In an autographic register of the kind in which a supply of continuous stationery strips is traversed step-by-step across a writing platen by feeding means operable by successive movements, a feed limiting device comprising an oscillatable driving member, a rotatable driven member having at least two circumferentially spaced aper-

tures in a circumferential surface, a movably mounted stop member engageable with each aperture of the driven member in turn when the member reaches a predetermined position in its rotation and on such engagement to prevent further rotation of the member, and a pawl making a pawl-and-ratchet one-way drive engagement with that aperture of the driven member which is then engaged by the stop member, said driving pawl being connected to the driving member for movement by the driving member in the driving direction and by such engagement and movement initially to engage the stop member and to apply a thrust, in a direction transverse to the driving direction, to the stop member to disengage the stop member from the engaged aperture, then, on continued movement of the driving member in the same direction, to rotate the driven member until the stop member engages a second aperture and prevents further movement of the driven member.

2. In an autographic register of the type in which a supply of continuous stationery strips is traversed step-by-step across a writing platen by feeding means operable by successive oscillatory movements of an external handle having a driving connection with the feeding means, a feed limiting device comprising a spindle constituting a driving member and arranged for oscillatory movements by the operating handle, a rotatable ring coaxial with and surrounding the spindle in spaced relationship, the ring constituting a driven member and having at least two apertures in its circumference, a stop pawl movably mounted adjacent the ring to engage in each aperture in turn to stop rotation of the ring, and a driving pawl carried by the spindle for rotation therewith to make pawl-and-ratchet one-way driving engagement with the apertures in the ring and to engage, at the beginning of each operation of the handle in the feeding direction, the aperture already engaged by the stop pawl, to push the stop pawl out of the aperture by such engagement and then on continued movement of the handle in the feeding direction to rotate the ring by its engagement with the aperture until the stop pawl by entering into the next aperture prevents further movement of the ring.

3. In an autographic register of the kind in which a supply of continuous stationery strips is traversed step-by-step across a writing platen by feeding means operable by successive movements of an external handle having a driving connection with the feeding means, a feed limiting device included in the said driving connection and comprising a spindle constituting a driving member and arranged for oscillatory movements by the operating handle, a rotatable ring coaxial with and surrounding the spindle in spaced relationship, the ring constituting a driven member operatively connected to the feeding means and having at least two apertures in its circumference, a stop pawl movably mounted outside the ring and arranged automatically to engage each aperture in turn from the outside to stop rotation of the ring in the feeding direction, and a driving pawl carried by the spindle and positioned in the space between the spindle and the ring, and arranged to make pawl-and-ratchet engagement with the apertures in the ring to effect a one-way feeding drive from the spindle to the ring and, at the beginning of each operation of the handle in the feeding direction, to make such pawl-and-ratchet engagement from

the inside of the ring with the aperture already engaged by the stop pawl from the outside, to pass through the aperture thereby pushing the stop pawl out of the aperture and then by its engagement with the aperture to rotate the ring on continued movement of the handle in the same direction until the stop pawl by engagement with the next aperture prevents further movement of the ring.

4. In an autographic register of the type in which a supply of continuous stationery strips is traversed step-by-step across a writing platen by feeding means operable by successive oscillatory movements of an external handle having a driving connection with the feeding means, a feed limiting device comprising a spindle constituting a driving member and arranged for oscillatory movements by the operating handle, a rotatable ring coaxial with and surrounding the spindle in spaced relationship, the ring constituting a driven member and having at least two apertures in its circumference, a stop pawl movably mounted outside the ring and arranged automatically to engage each aperture in turn from the outside to stop rotation of the ring, and a driving pawl carried by the spindle and positioned in the space between the spindle and the ring and arranged to make a pawl-and-ratchet one-way feeding drive from the spindle to the ring and, at the beginning of each operation of the handle in the feeding direction, to make such pawl-and-ratchet engagement from the inside of the ring with the aperture already engaged by the stop pawl from the outside, to pass through the aperture thereby to push the stop pawl out of the aperture and then by its engagement with the aperture to rotate the ring on continued movement of the handle in the same direction until the stop pawl by engagement with the next gap prevents further movement of the ring.

5. In an autographic register of the kind in which a supply of continuous stationery strips is drawn from a zig-zag pack and is traversed step-by-step across a writing platen by feeding means operable by successive movements of an external handle having a driving connection with the feeding means, a feed limiting device included in the said driving connection and comprising a spindle constituting a driving member and arranged for oscillatory movements by the operating handle, a rotatable ring coaxial with and surrounding the spindle in spaced relationship, the ring constituting a driven member operatively connected to the feeding means and having four equally spaced apertures in its circumference, a stop pawl movably mounted outside the ring and arranged automatically to engage each aperture in turn from the outside to stop rotation of the ring and a driving pawl carried by the spindle and positioned in the space between the spindle and the ring and arranged to make a pawl-and-ratchet one-way feeding drive from the spindle to the ring and, at the beginning of each operation of the handle in the feeding direction, to make such pawl-and-ratchet engagement from the inside of the ring with the aperture already engaged by the stop pawl from the outside, to pass through the aperture thereby to push the stop pawl out of the aperture and then by its engagement with the aperture to rotate the ring on continued movement of the handle in the same direction until the stop pawl by engagement with the next aperture prevents further movement of the ring.

6. In an autographic register of the kind in

which a supply of continuous stationery strips is traversed step-by-step across a writing platen by feeding means operable by successive movements of an external handle having a driving connection with the feeding means, a feed limiting device included in the said driving connection and comprising a spindle constituting a driving member arranged for oscillatory movements by the operating handle, a rotatable ring coaxial with and surrounding the spindle in spaced relationship, the ring constituting a driven member and having at least two apertures in its circumference, a stop pawl movably mounted inside the ring and arranged automatically to engage each aperture in turn from the inside to stop rotation of the ring in the feeding direction, and a driving pawl rotatable by the spindle and positioned outside the ring and arranged to make a pawl-and-ratchet engagement with the apertures in the ring to effect a one-way feeding drive from the spindle to the ring and, at the beginning of each operation of the handle in the feeding direction, to make such pawl-and-ratchet engagement from

the outside of the ring with the aperture already engaged by the stop pawl from the inside, to pass through the aperture thereby pushing the stop pawl out of the aperture and then by its engagement with the aperture to rotate the ring on continued movement of the handle in the same direction until the stop pawl by engagement with the next aperture prevents further movement of the ring.

PERCY ALFRED FLAWN.
